WHIRLING TOY FOR BALANCING AN OBJECT

Grant L. Southworth, 261 South 100 West,
Kaysville, Utah

Filed May 20, 1964, Ser. No. 80,076

Term of patent 3½ years

(Cl. D34—15)

FIGURE 1 is a front view of a whirling toy for balancing an object, showing my new design;

FIGURE 2 is a side elevational view thereof; and

FIGURE 3 is a view taken on line 3—3 of FIG. 2.

I claim:

The ornamental design for a whirling toy for balancing an object, as shown.
